UNITED STATES PATENT OFFICE.

IRA D. MORGAN, OF PITTSBURGH, PENNSYLVANIA, ASSIGNOR OF ONE-HALF TO J. SCOTT MORGAN, OF PITTSBURGH, PENNSYLVANIA.

BACK-DRAFT DAMPER.

Application filed December 18, 1926. Serial No. 155,682.

The invention relates to back draft dampers for use in ventilating systems. The flaps employed in dampers of this kind are of thin sheet aluminum, designed to operate from 5 very light air currents, and should be practically noiseless in operation. Heretofore, it has been the practice to hinge the flaps on metal wires extending transversely of a rectangular damper frame, so that the lower 10 edge of each flap engages the upper portion of the flap next below. The lower edges of the flaps are provided with felt strips designed to act as silencers and to increase the effectiveness of the seals between the flaps. 15 These dampers have been more or less unsatisfactory for several reasons. Due to the sagging of the supporting hinge wires, the flaps are liable to rub at their edges on the supporting frame and make an objectionable 20 noise, which is increased by the vibration incident to the thin shell-like flaps striking together. Further, the weight of the felts upon the flaps reduces their freedom of movement, thus reducing the flow of air 25 through the damper, particularly with a light draft. The present invention is designed to overcome the foregoing objections, and has for its primary objects, the provision of an improved construction, (1) in which 30 there is no sagging of the supports for the flaps; (2) in which the flaps swing freely without any rubbing action on adjacent parts; (3) in which the noise incident to one flap striking against another is avoided, 35 and, (4) in which the weight of the felts is removed from the flaps, so that they swing more freely, and thus give a better flow of air through the damper under light draft 40 conditions than was the case with the construction heretofore used.

Briefly stated, the foregoing results are secured by providing the rectangular damper frame with a series of stiffening bars, to which the flaps are hinged, and which carry 45 rearwardly projecting felt strips adapted to contact with the swinging edges of the flaps. The bars stiffen the rectangular supporting frame, and in addition, each performs the dual function of supporting the flap lying beneath, and of holding the felt for engaging 50 the flap lying above it. Due to the rigidity of the bars and the stiffness of the structure as a whole there is no sagging of the flaps, which always maintain their original 55 freedom of movement, thus avoiding any

scraping noises incident to the edges of the flaps moving over the supporting frame. The vibration and noise incident to the flaps engaging the felts is also reduced to a minimum, due to the firm support of the felts 60 on the relatively rigid transverse bars. The flaps also swing with greater freedom than those heretofore used, because of their reduced weight incident to the transfer of the felts from the flaps to the bars. Certain 65 embodiments of the invention are illustrated in the accompanying drawings, wherein:

Figure 1 is a front elevation. Figs. 2 and 3 are sections respectively on the lines II—II 70 and III—III of Fig. 1. Fig. 4 is a partial rear elevation on an enlarged scale. Figs. 5 and 6 are sections on the lines V—V and VI—VI respectively of Fig. 4. Fig. 7 is an enlarged section through one of the transverse bars. And Fig. 8 is a section through a modified form of transverse bar.

The rectangular frame of the damper consists of the sheet metal side members 1, 2, 3 and 4, stiffened on its forward side by the 80 angle 5 soldered or otherwise secured to the side members. Suitable corner stiffeners 5^a and 5^b are also provided to increase the rigidity of the frame. Extending longitudinally of the frame is the bar 6 of T-cross 85 section, such bar being secured at its ends to the members 3 and 4. Lying transversely of the frame are the bars 7, 7, 7, etc. soldered at their outer ends to the members 1 and 2 and at their inner ends to the T-bar 6. 90

The transverse bars 7 are preferably of the cross section indicated in Figs. 5 and 7, being formed of strips of sheet metal bent double to give additional stiffness and to provide the lips 8, 8, and also bent into angular form which further adds to the stiffness. Between the lips of each bar is mounted a strip 9 of soft flexible material, such as 95 felt, such felt strips serving to cushion the impact of the metal flaps as later described. 100

Hinged to each of the bars 7 is a flap 10 of very thin light metal, such as aluminum. Each of the flaps is provided with a pair of clips 11, 11 riveted in position and engaging the horizontal portions of the hangers 12, 12. 105 The vertical portions of these hangers extend through the lips 8, 8 of the bars 7, and through the felt strips 9 lying between the lips, so that the hangers perform the function of retaining the felt in position. The 110

upper ends of the hangers are bent into the form of eyes to retain them in position. The lower edge of each flap engages the felt strip on the bar next beneath.

5 The device, as thus constructed, is very rigid, due to the transverse bars, and to the stiff construction of the supporting frame. The flaps swing very freely, because of their light weight and for this reason and because 10 of the stiffness of the cross bars, the noise and vibration produced when the flaps engage the felts is reduced to a minimum. The rigidity of the structure also obviates any sagging of the flaps and consequent rubbing 15 upon the frame and interference with their movement, such as has been common with flaps supported upon transverse wires.

Fig. 8 illustrates one of a number of modified forms of transverse bars which might 20 be employed, although the angular form as heretofore described is preferred, because of its greater stiffness. This bar 13 of Fig. 8 comprises a sheet of metal bent into U-shape with a felt 14 held between the metal lips 25 as in the other form of bar.

What I claim is:

1. In combination in a back draft damper, 20 a rectangular metal frame, a series of transverse bars extending across the frame at

30 spaced intervals, a strip of soft flexible material carried by each bar and projecting to the rear thereof, and a flap of thin sheet metal hinged at its upper edge to each of said bars and engaging at its lower edge the strip on the next lower bar, each of said bars 35 being formed of sheet metal doubled upon itself and bent into the cross section of an angle with one flange vertical and the other one horizontal, and having said strip clamped between the two parts thereof.

2. In combination in a back draft damper, 40 a rectangular metal frame, a series of transverse bars extending across the frame at spaced intervals, and each comprising a sheet metal strip bent upon itself so as to provide a pair of spaced lips with the space therebetween openings to the rear, a strip of soft flexible material lying between each pair of lips and extending to the rear thereof, hangers extending through said lips and through 45 said strips, and flaps of thin sheet metal hinged at their upper edges to said hangers, and at their lower edges engaging said strips.

50 In testimony whereof, I have hereunto subscribed my name this 17th day of December, 1926.

IRA D. MORGAN.
